(57) **CLAIM**

(22) Filed: **May 21, 2012**

The ornamental design of the combined food jar and lid with oval grips, as shown and described.

(51) LOC (9) Cl. **07-07**

DESCRIPTION

(52) U.S. Cl.

USPC **D7/629**

(58) **Field of Classification Search** D7/601,

FIG. 1 is a perspective view taken from the upper, front, right-hand side of the combined food jar and lid with oval grips of the present invention;

D7/602, 629, 538–542, 612–615; D9/502, D9/541, 574, 575, 516; 220/780–806, 574–575, 220/675, 573.1, 660, 260, 288, 326, 236, 220/4.21, 4.24, 4.27, 669–673, 23.83, 23.4

FIG. 2 is a perspective view taken from the lower, back, left-hand side of the combined food jar and lid with oval grips of FIG. 1;

See application file for complete search history.

FIG. 3 is a side elevational view of the left side of the combined food jar and lid with oval grips of FIG. 1;

(56) **References Cited**

FIG. 4 is a front elevational view of the combined food jar and lid with oval grips of FIG. 1;

U.S. PATENT DOCUMENTS

FIG. 5 is a side elevational view of the right side of the combined food jar and lid with oval grips of FIG. 1;

4,399,926 A * 8/1983 Eidels-Dubovoy 220/288
